DISHWASHING MACHINE

Edgar S. Stoddard, Berwyn, Ill., assignor to The Conover Company, Chicago, Ill., a corporation of Illinois

Application July 16, 1928, Serial No. 293,197

14 Claims. (Cl. 141—9)

This invention relates to improvements in dish washing machines, and it more particularly relates to improved rack arrangements for holding the dishes and similar objects to be washed in 5 the interior of the machine.

An object of this invention is to provide an improved rack arrangement which is adapted to 10 position all the dishes, saucers, cups, glasses, silverware, etc. in the interior of the washing chamber so as to obtain an economical utilization of 15 the space within such washing chamber.

Another object of this invention is to provide 20 an improved rack arrangement which is adapted to retain all the articles to be cleansed and rinsed 15 in positions such that all surfaces thereof will be effectively exposed to the cleansing and rinsing liquids when the machine is in operation.

A further object of this invention is to provide 25 an improved rack arrangement which is self-cleansing and which will be cleansed and rinsed at the same time as the articles which it contains.

A still further object of this invention is to provide 30 an improved rack arrangement for dish washing machines of the spray projection type.

Other objects will appear during the course of 35 the following specification.

Although this invention is broadly directed to 40 improvements in connection with all dish washing machines, it is especially directed to improvements to be used in connection with the centrifugal spray projector-type of washing machines, which are more fully described and shown in the copending application, Serial Number 353,841 filed January 24, 1920 now Patent 1,679,465, 45 granted August 7, 1928.

The functioning of this type of machine depends upon the operation of a small unencased screw propeller-like impeller, with curved blades, which impeller rotates at a high velocity of the 50 order of 1,000 to 2,000 R. P. M. in the lower part of the tank of the machine. Only the lower part of this impeller is immersed in the shallow liquid pool in the lower part of the tank. The shallow liquid pool in the lower part of the machine is 55 maintained in relatively quiescent condition during the operation of the machine. As it turns, the impeller elevates the liquid from its lower screw propeller portions to its upper concavo-projectors which throw the cleansing liquid at a tremendous velocity directly upon, or into, the objects to be cleansed. Since there are no baffles or deflectors to break the force of the liquid, the total force of the projected mass of liquid is effective for cleansing purposes. Although the 60 velocity of the cleansing liquid is very high, the

volume of cleansing liquid is very small, and as a result a very effective cleansing is obtained with a minimum and most efficient use of soap and water. The projected mass of liquid at the same time keeps the interior of the tank of the machine clean and causes all the food particles and other solid matter to collect at the bottom of the casing from whence they can be readily removed. In the operation of this unencased impeller, it is important that only the lower portion of the impeller be immersed in water since if the impeller 5 be totally immersed, it will not result in an efficient cleansing action. In view of the fact that the dishes and other objects are kept out of contact with the body of liquid contained in the 10 bottom of the tank, and the cleansing is solely due to contact with the projected mass of liquid, it is important that the proper operating conditions be maintained for producing such a cleansing 15 action.

The following drawings illustrate one embodiment of the invention as applied to the centrifugal spray projector-type of dishwashing machines, to which the invention is by no means restricted.

Figure 1 represents a side sectional view of the 20 washing machine and the racks in position;

Figures 2, 3, 9 and 10 represent additional showings of the lower rack structures; and

Figures 4, 5, 6, 7 and 8 represent additional showings of the upper rack structures. 30

In Figure 1 the washing machine is composed of a vertical cylindrical tank 11 which is provided with a cover 12 and three symmetrically positioned legs 13 which ride upon the rollers 14 so that the washing machine can be readily 35 moved from place to place. The tank is provided with two strengthening ribs 15 and 16 the former being adjacent to the top and the latter adjacent to the bottom thereof, and it is also provided with a centrally draining bottom 17. To 40 the lowest portion of the centrally draining bottom is attached a well chamber 20 in the lowest compartment 21 of which is positioned a centrifugal pump 22. The cleansing and rinsing liquids are adapted to be admitted to the tank by the 45 adjustable swinging conduit 25. In the lowest central portion of the tank is positioned the impeller 35 which is driven by the motor 36. The motor is in part suspended from the tank by means of the well casting 20 and is in part supported from the legs by means of the spider 37. The lid 12 is provided with a vent 40 and with a support rod 41 and guide rods 42 which are adapted to support the lid when in inverted horizontal 50 position.

55

The lower rack structure is shown in section in position in the machine upon Figure 1. It is shown in top view removed from the machine in Figure 3 with the silverware rack in position. 5 Figure 2 is a side view of the lower rack with the silverware holder removed. Figure 9 is a side view of the silverware holder removed from the lower rack. The lower rack is provided with three different sized radial dish-holder portions, 10 sections of the smallest and medium size being shown in Figure 1 and of the largest size in Figure 10. The lower rack is adapted to hold the larger plates and dishes, and also knives, forks 15 and spoons, during the cleansing operation. It is preferably supported on the bottom of the tank by four symmetrically positioned legs 45, but it also can be supported on an impeller guard member (not shown). It will be noted that the lower legs 45 are so positioned that they will rest 20 upon the lower dished conical bottom of the tank 11 near the jointure of the bottom with the walls of the tank. The legs 45 also are adapted to support the rack when it is outside the tank so as to prevent any of the downwardly projecting portions 25 of the dishes from being chipped and otherwise marred.

The lower rack contains a special perforated sheet metal holder 46 (see Figures 1, 3 and 9) which is provided with the handles 47. The holder 46 is so constructed and is so positioned that the knives, forks and spoons contained therein will receive the full effect of the cleansing spray. It will be noted that the holder is arcuate in shape and that its inner wall is lower than its 35 outer wall. It is adapted to fit in the outer circle of the lower rack. The perforated sheet metal holder as shown in the present embodiment of the invention is divided into several compartments, in the present embodiment four in number, by the walls 48. These compartments are of such width as to maintain the knives, forks, spoons and similar objects in vertical position and prevent them from lying over on their sides. The outside wall 49 of the sheet metal holder is 40 higher than the inside wall 50. This also assists 45 in holding the knives, forks, spoons, etc. in proper position. The top edges of the walls are rolled or bent over to make a neat finish. The angular location of the silverware container is determined by the wire 53 on the side in the direction 50 of rotation. It is located radially by the wires 60 and 68 (see Figures 1, 2 and 3). The holder 46 is supported in the U-bent wires 51 the bottoms 55 of which are provided with offset portions 52 (see Figures 1 and 2). These offset portions 52 are welded or soldered to the top of the intermediate circular wire 61.

A series of upstanding wire dish holders are 60 arranged in the lower rack. These are adapted to position and retain the large size dishes and plates. The smaller vessels are positioned in the upper rack structure which will be subsequently described. One set of these wire holders extends between the inner ring 65 and the intermediate 65 ring 66 (see Figures 1, 2, 3 and 10). The holders between the rings 65 and 66 comprise upstanding wires 71 and 72 spaced about the central portion of the rack and include arcuate separator strips 69 arranged in an approximately 70 horizontal position for spacing and supporting the flat dishes on edge with their faces substantially vertical and tangent to the mean circumference of the water impeller 35 in the direction of its rotation. The wire holders are so formed 75 as to position the dishes in such a manner that

the tangential line on which they are set will intersect the tangentially projected water. The projected water, which is in the form of a spray during the operation of the machine, may be considered as being initiated from the middle of the 5 spoon-shaped projector at the top of the impeller. The holders of the other set extend between the intermediate concentric wire ring 66 and the outer concentric wire ring 68. These holders are adapted to support the largest dishes on edge 10 adjacent to the wall of the washing chamber and transverse to a radius.

The inner holders between the rings 65 and 66 are arranged in three groups adapted to hold different sized plates or dishes. The group 15 extending from the radial wire 53 to the radial wire 87 is adapted to hold the plates of large diameter, the group extending from the radial wire 87 to the radial wire 88 is adapted to hold the plates or dishes of medium diameter and the 20 group extending from the wire 88 to the wire 53 is adapted to hold the dishes of small diameter.

The intermediate dish-supporting ring segments 80, 83, 70, 81, 82, and rings 66 and 61, and the outer dish-supporting ring 67 and ring 68 25 are concentric with the center 43 of the lower rack which also coincides with the center of the machine. The concentric ring segment 61 and ring 67 are adjacent to the bottom of the rack and on substantially the same level. The ring 30 66 is slightly above and to the inside of the ring segment 61. The ring 68 is above, and to the outside of, the ring 67 and is the terminating outer ring of the rack. The concentric ring 66 and ring segments 70, 82 and 83, and 81 and 80 function 35 as rests for the edges of the dishes. The pair 66 and 70 are the lowest, the pair 82 and 83 are higher than, and at the same radial distance as, the pair 66 and 70, respectively, and the pair 81 and 80 are the highest and at shorter radial 40 distances than the other pairs. The concentric wire ring 66 extends through the entire rack, the ring segment 70 extends through only the section 53-87 for the large dishes, the ring segments 82 and 83 through only the section 87-88 for the 45 intermediate dishes and the ring segments 81 and 80 through only the section 88-53 for the small dishes. The innermost ring 65 is somewhat off center or eccentric to the ring 66 and the outer rings and ring segments. This results 50 in the variation of the length of the wire holders between the rings 65 and 66 dependent upon their particular angular position in the lower rack.

The largest dishes are adapted to be positioned 55 in the sections 53-87 adjacent to wire 53 in the direction of rotation of the impeller. In this section 53-87 (see Figures 3 and 10), the concentric ring 66 and ring segment 70 form rests for the dishes, the outer wire 66 being located above the inner wire 70 so as to cause the plates 60 to roll slightly toward the central ring as they are placed therein. The vertical heights of the arcuate wires 69 are such that the plates can be readily loaded and unloaded by taking hold 65 of them above the wires. The arcuate wires 69 are shaped on top so as to conform to the curvature of the dishes slightly so that there will be no pressure to cause the edges of the dishes to chip.

Adjacent to the section for large dishes, in the 70 direction of impeller rotation, is the section 87-88 adapted to hold dishes of intermediate diameters. This section differs from the section for large dishes by having the concentric ring segments 82 and 83 slightly higher than the cor- 75

responding ring 66 and ring segment 70, although at the same radial distance. The arcuate wires 86 and the vertical wires 84 and 85 serve to support and retain the dishes in the desired positions. 5 The arcuate wires 86 are at the same height as, but are shorter than, the curved portions 69 due to the eccentricity of the central ring 65.

In the section adapted to hold the smallest dishes or plates radially in front of the space 10 provided for the silver rack (see Figures 1 and 3) are positioned a number of short arcuate wires 73 similar to the wires 69 and 86 with vertical supporting wires 74 and 75 attached to the concentric ring portions 80 and 81 which are at 15 about the same height. The wire 60 and the short wires 62 serve to prevent the smaller dishes from being rolled out of this section into the space radially adjacent to the silverware holder and falling into the liquid pool in the bottom of tank.

20 The concentric ring sections 70, 83 and 80 form the lower inner support of the plates placed in the wire frames around the impeller. The pockets are all approximately of such size that the tops of the plates of gradated sizes will be 25 in the same position vertically with relation to the horizontal projecting plane of the impeller. The arcuate wires 69, 86 and 73, forming the top of the pockets, are all on the same horizontal plane. The outer concentric ring 66, and ring 30 segments 82 and 81 tend to roll the dishes into position on the wires 70, 83 and 80 respectively. The inner ends of the arcuate wires 69, 86 and 73 terminate in the eccentric ring 65 (Figures 1, 3 and 10). The vertical wires 72, 84 and 75 are 35 continuations of the outer ends of the arcuate wires 69, 86 and 73. The vertical wires 72 and 84 terminate in the concentric ring 66 and the wires 84 are also attached to the concentric ring segment 82 a short distance above their point 40 of attachment to the ring 66. The vertical wires 71, 85 and 74 extend between, and are attached to, the upper arcuate wires 69, 86 and 73 and the lower inner concentric ring portions 70, 83 and 80, respectively.

45 The concentric wires 101, 103 and 104 and the radial wires 102 are positioned beneath and also centrally in front of the section 53-87 to prevent dishes from falling onto the rotating impeller. The concentric wire 104 serves a similar purpose also for the section 87-88 designed to hold 50 dishes of intermediate size.

Another set of wire holders extends between the intermediate ring 66 and the outer ring 67 and ring 68. The radial U-shaped wires 76 are attached to and below the concentric rings 61, 66, 67 and 68 and with these rings form the outer dish holders of the lower rack (see Figures 1, 3 and 10). The U-wires 76 are so angularly spaced that only a proper number of the large dishes 55 may be positioned around the outer portion of the lower rack. The inner lower edge of these large dishes in the outer rack will rest against either the inner vertical portions 77 of the U-wires 76 or against the concentric ring 61 and the bottom of the U-wires 76, depending upon 60 their depth, the deeper dishes resting against the wires 77 and the shallow dishes against the wire 61. These plates are caused to lean backward so that they will face the center of the machine and not come into contact with the smaller plates located in the central holders. The backs of these 65 dishes will rest against the outer vertical portions 78 of the U-wires 76 and the ring 68. The lower rack is provided with two vertically extending handles 79. The lower rack is adapted to support

10 dinner plates of 9 to 10" diameter, on the outside holders between the rings 66 and 68 and in the inside radial holders, 14 dinner plates of 9 to 10" diameter, 10 salad plates of 7-8" diameter and 10 tea saucers or bread-and-butter plates of 5 5-6" diameter.

The upper rack structure is shown in position in the machine in Figure 1 and is shown removed from the machine upon Figures 4, 5, 6, 7 and 8. It consists of two concentric sections, an inner 10 section shown on Figures 4, 6, 7 and 8 and an outer section shown in Figures 5 and 6. The inner upper rack is supported from the outer upper rack and may consist of different embodiments, such as that shown in Figure 4 or that shown 15 upon Figures 7 and 8. The embodiment shown on Figures 7 and 8 is especially designed to be utilized as a small dish holder, whereas the embodiment shown upon Figures 4 and 6 is adapted to be a deep vessel holder. 20

The inner upper rack shown as Figures 1, 4 and 6 consists of a series of radial and concentric wires which are welded together to form an upwardly pointing conical section. There are a series of short radial wires 90 and a series of longer 25 radial wires 91. The longer radial wires 91 terminate at and are welded to the top of the innermost concentric ring 92 while the shorter radial wires are welded to and on top of the next to the inner concentric ring 93. Several of the radial wires 90 or 91 are provided with projecting portions 94 which hook over and support the inner rack upon the innermost ring 95 of the outer section. The radial wires 90 and 91 are also welded to intermediate concentric wire 96. The 30 network of radial wires 90 and 91 and concentric wires 92, 93 and 96 form an upwardly pointing frusto-conical section which forms a bottom for the deep vessels which are supported face downward. To the edge of the upwardly pointing 35 conical section (see Figure 4) is attached a cylindrical section formed by the upwardly turned parts of the radial wires 90 and 91 and by the concentric wires 97 and 98 in which most of the wires 90 and 91 terminate. Certain of the 40 radial wires as indicated at 99 are continued upwardly and are welded to a concentric ring 100. The upper concentric ring 100 is supported by a minimum of vertical wires 99 and at such a distance above the concentric ring 98 that vegetable 45 and similar deep vessels can be placed between the two concentric rings 98 and 100 when they are supported by both the inner and outer sections of the upper rack. The concentric ring 100 is positioned above the concentric ring 98 50 a sufficient distance to support effectively the taller type of glass-ware adjacent to their upturned bottoms. The conical bottom formed by the welded radial wires 90 and 91 and the concentric rings 92, 93 and 96 is inclined to the horizontal at a sufficient angle to admit the cleansing streams to strike the center of inner bottoms of the upturned vessels and provide proper drainage for the water from the upturned bottoms. This angle is about 10 to 20°, usually about 15° 55 for the particular impeller shown.

The upper rack illustrated upon Figure 4 and shown in position upon Figures 1 and 6 may be replaced if desired by the rack shown upon Figures 7 and 8. The rack shown upon Figures 7 70 and 8 is provided with a series of tall radial downwardly faced U-bent holders 110 to the outside of which are attached a lower set of L-bent holders 111.

The rack is provided with a conical bottom 75

formed by the welded concentric wires 112, 116 and 117, the long radial wires 113 and the short radial wires 114. The outermost concentric ring 118 of the rack is provided with several symmetrically positioned hook shaped portions 115 which are adapted to position this embodiment of the inner upper rack upon the innermost concentric ring 95 of the outer upper rack. The vertical holders of this particular embodiment of the inner upper rack are not exactly radial but are set tangential to the mean projecting circle of the impeller. The lower ends of the U-shaped holders 110 are welded to the concentric rings 116 and 117 and the L-shaped holders are welded to the outermost ring 118 and the outer legs 119 of the U-shaped wires 110 about one-third the distance from the ring 117 to the top of the U-bent wire 110. The short radial wires 114 extend between the rings 116 and 117 to which they are welded and they are symmetrically positioned between the long radial wires 113. The long radial wires 113 extend between the rings 112 and 117 and are welded to these rings and also rings 116 on the underside. These are also symmetrically positioned around the circumference. The combined U-bent wires 110 and L-shaped wires 111 provide sufficient height and width for supporting tea saucers and bread-and-butter plates of about 5" diameter in a proper vertical position on the concentric rings 116 and 118. The ring 118 is higher than the ring 116 to prevent dishes from rolling out of their position during the washing operations. The low L-shaped wires provide a short side on the supporting rack which permits easy loading and removal of small diameter dishes, such as pats of about 2 1/4" diameter without sacrificing the efficiency of rack for holding larger 5" plates. These smaller dishes are supported on the ring 117 and held in position by the concentric rings 116 and 118. The principal vertical supporting wires 119 and 120 pass completely between the dishes insuring easy access to the soiled parts for the projected cleansing stream.

The outer upper rack is shown in the position 45 in the tank in Figure 1. It is shown in vertical cross section in Figure 5 removed from the tank, and is shown in top view upon Figure 6 with an inner upper rack such as that shown in Figure 4 in position. The outer upper rack consists of an 50 inner upwardly-pointing conical section which is formed by a series of concentric wires 95, 127 and 128 upon the tops of which are welded the radial wires 121. Attached to the outside of this conical section is an outwardly curved portion 55 which is formed by the outwardly curved portions of the radial wires 121, being welded to the two concentric wires 129 and 130. The outer upper rack terminates in a downwardly-pointing conical section, the upper side of which is welded to 60 ring 123. To the ring 123 are welded the small legs 124 which are symmetrically positioned so as to support the upper rack structure from the upper bead 15 of the tank 11. The upper rack is provided with two handles 125. The inner conical section of the outer upper rack extends from 65 the innermost ring 95 to the bends 131 in the radial wires 121. The intermediate outwardly curved section extends between the bends 131 and 132 in the radial wires 121. The outer conical section extends from the bends 132 in the radial wires 121 to the outermost ring 123. The central conical section of the outer upper rack 70 which is formed by the concentric wires 95, 127 and 128 and the radial wires 121 is given a slope 75 of about 35° to 45° from the horizontal. The

inner side of this conical section faces the lower center of the machine. The curved intermediate portion formed by means of the concentric wires 129 and 130 is adapted to support the sides of the cups in proper position for washing and prevents them from overturning. The terminating downwardly-pointing conical section between the bends 132 and the ring 123 is adapted to support glasses so that they will rest firmly on the lower conical section between the ring 95 and the bends 131 in a position where they will be effectually cleansed.

The legs 124 space the outer upper rack away from the side of the tank and permit the spray generated by the impeller to effectually cleanse 15 the space between the outer ring 123 and the tank. The doubly bent radial wires 121 are symmetrically positioned on the terminating rings 123 and 95 and the intermediate rings 121, 128, 129 and 130 so that average sized tumblers will 20 be supported in all cases by two of the radial wires in the upper conical section between the bends 132 and the ring 123 and will rest upon two or more radial wires in the inner conical section between the bends 131 and the ring 95. The intermediate rings 127, 128, 129 and 130 are so positioned that they will form a protective mesh to prevent dishes of small dimensions of approximately 2 1/4" diameter from falling through the interstices. The outer upper rack has a capacity 25 of about 16 cups or glasses. The embodiment of the inner upper rack shown in Figure 4 has a capacity of 9 glasses or cups. The capacity of the embodiment shown in Figures 7 and 8 is about 24 bread-and-butter plates or tea saucers. 30 The overhanging hooks 94 or 115 of the inner upper racks are adapted to suspend the bottom of the inner upper rack below the inner edge of the outer upper rack, but not sufficiently below to prevent the water spray projected by the impeller 35 from effectually contacting with the articles on the outer portion of the upper rack. 40

The rack structures may be made from stainless alloys or they may be coated with glass or other enamels to prevent them from rusting and 45 from marking or marring the dishes. They are preferably colored light gray so as to give them a sanitary appearance.

The rack arrangements of the present application constitute a modification of the rack arrangements shown and described in the copending application Serial No. 271,681 filed April 21, 1928, which has matured into Patent No. 1,905,523, granted April 25, 1933, and they are especially adapted for use in large diameter washing machines, say about 29" in diameter. 50

What is claimed is:

1. In a rack for a dish washing machine provided with a vertical washing chamber and with a water actuating device adjacent the lower part of said chamber, a silverware holder adapted to be placed in the lower and outer part of the washing chamber, the walls and bottom of said silverware holder being formed of a mesh, the inner and outer walls being arcuate in shape, said inner wall being substantially lower than the outer wall, and inwardly converging partitions connecting said inner and outer walls to form therebetween a series of compartments for receiving silverware, the distance between the partitions being small so as to prevent a knife, fork or a spoon from lying horizontally in any compartment.

2. In a spray projecting dishwashing machine, a silverware holder adapted to be placed in the lower and outer part of the washing chamber, the

- walls and bottom of said silverware holder being formed of a screen with two opposite walls of concentric arcuate shape, the top edge of one of said walls being lower than the other.
5. In a rack for supporting flatware in a dish-washing machine, a plurality of groups of dish holders arranged in spaced relation about the center of said rack, said dish holders having bottom elements and upstanding inwardly extending partition elements, the bottom elements of each of said groups of dish holders being positioned as a unit at progressively greater elevations around said center than the bottom elements of the next preceding group.
10. A rack for supporting flatware in a dish-washing machine, comprising a plurality of upstanding strips arranged in spaced relationship about the center of the rack and having separator strips extending from their upper ends toward the central portion of the rack, and strips extending transversely of said separator strips and connecting the lower portions of said upstanding strips to form rests for dishes supported on edge between the separator strips, said transversely extending strips being arranged in groups of different elevations.
15. In a rack for supporting flatware in a dish-washing machine, a plurality of groups of dish holders, said holders being formed in part by inwardly directed upstanding wire partitions arranged in spaced relation about the center of the rack, and having bottom elements, said groups of holders around the center being progressively smaller in size with their bottoms at progressively greater elevation.
20. A rack for supporting flatware in a dish-washing machine, comprising a plurality of upstanding strips arranged in spaced relationship about the center of the rack and having separator strips extending from their upper ends toward the central portion of the rack, and arcuate strips 20 extending transversely of said separator strips and connecting the lower portions of said upstanding strips to form rests for dishes supported on edge between the separator strips, said arcuate strips being arranged in groups of different elevations.
25. In a rack for supporting flatware in a dish-washing machine, an inner ring, a plurality of substantially concentric outer ring segments disposed around and below the inner ring, said outer ring segments having progressively greater elevations, and wire loops arranged in spaced relation and connecting said outer ring segments with said inner ring to form groups of dish holding compartments.
30. A rack for supporting flatware in a dish-washing machine, a plurality of substantially concentric outer ring segments arranged around the center of the rack at different elevations, an inner ring eccentric to said outer ring segments and being nearer the segment of greatest elevation, and wire loops arranged in spaced relation 30 and connecting said outer ring segments to said inner ring to form groups of dish holding compartments.
35. A rack for supporting flatware in a dish-washing machine, a plurality of substantially concentric outer ring segments arranged around the center of the rack at progressively greater elevations, an inner ring above and eccentric to said outer ring segments and being nearer the segment of greatest elevation, wire loops arranged 35 in spaced relation and connecting said outer ring segments to said inner ring to form groups of dish holding compartments, inner ring segments positioned between said outer ring segments and said inner ring, and wires extending upwardly from said inner ring segments to said loops.
40. A rack for supporting flatware in a dish-washing machine, a plurality of substantially concentric outer ring segments arranged around the center of the rack at progressively different elevations, inner ring segments corresponding to said outer ring segments, an inner ring above and eccentric to said outer ring segments and being nearer the segment of greatest elevation, wire loops arranged 40 in spaced relation and connecting said outer ring segments to said inner ring to form graduated groups of dish holding compartments, partition wires extending upwardly from said inner wire segments to said wire loops, an outer ring encompassing said outer ring segments and spaced therefrom, and transverse
- wires extending across said space to form a dish support.
45. A rack for supporting flatware in a dish-washing machine, comprising a plurality of upstanding strips arranged in spaced relationship about the center of the rack and having separator strips extending from their upper ends toward the central portion of the rack, and strips extending transversely of said separator strips and connecting the lower portions of said upstanding strips to form rests for dishes supported on edge between the separator strips, said transversely extending strips being arranged in groups of different elevations.
50. A rack for supporting flatware in a dish-washing machine, comprising a plurality of upstanding strips arranged in spaced relation about the center of the rack and having separator strips extending from their upper ends toward the central portion of the rack, a ring encompassing the upstanding strips and spaced outwardly therefrom to afford an intervening space for reception of dishes, inwardly extending strips across the bottom of said space to form rests for 50 dishes supported between said ring and the upstanding strips, and strips extending transversely of said separator strips and connecting the lower portions of said upstanding strips to form rests for dishes supported on edge between the separator strips, said transversely extending strips being arranged in groups of different elevations.
55. A rack for supporting flatware in a dish-washing machine, a plurality of outer ring segments forming a substantially circular outer rack 55 portion, an inner ring eccentric to said outer rack portion, and wire loops arranged in spaced relation transversely to said outer rack portion and said inner ring and connecting the same to form dish holders of progressively smaller size.
60. A rack for supporting flatware in a dish-washing machine, an outer circular rack portion, an inner circular rack portion eccentric to said outer portion and partition members arranged in spaced relation transversely to said inner and outer rack portions and connecting the same to form dish holders of progressively smaller size.
65. A rack for supporting flatware in a dish-washing machine, an outer circular rack portion and an inner circular rack portion spaced therefrom and cooperating with said outer rack portion to form a plurality of bottom supporting elements from said circular rack portions for said flatware, a plurality of inwardly extending upstanding wire partitions arranged in spaced relation on said bottom supporting elements around the center of the rack, said bottom supporting elements being positioned at progressively greater elevations around said center.
